UNITED STATES PATENT OFFICE

ALEXANDER MOODIE, OF EAST ORANGE, NEW JERSEY, ASSIGNOR TO PENDENNIS TOILETRIES, INCORPORATED, OF NEW YORK, N. Y., A CORPORATION OF NEW YORK

COSMETIC CONTAINER

Application filed July 22, 1929. Serial No. 380,222.

My invention relates to cosmetic containers and refers particularly to containers adapted for holding powder compacts and cosmetic sticks.

5 One of the objects of my invention is a device in which one, or more, powder compacts may be carried in conjunction with a cosmetic stick, or pencil, the holder for the latter acting as a means for holding the compact 55 container in position for the use of a mirror, also carried by the compact container.

10 Devices of this character, should be small in size and should contain two powder compacts and a cosmetic pencil, such as lip rouge 15 or eyebrow applications, the compacts must be easily accessible and must be protected from danger and a mirror is necessary for the proper application of the several toilet preparations.

15 It is also desirable that these several articles be combined in a single container.

20 The device of my invention accomplishes all of the above, and other, desirable objects and possesses attributes of great convenience 25 and usefulness.

25 In a general way, my device comprises a container capable of containing one, or more, powder compacts, and one, or more, mirrors, the handle of the container being adapted not 30 only for convenience of holding the mirror, but also as a means for containing, and carrying, a cosmetic pencil, all of which will be evident upon a consideration of my specification and its accompanying drawings.

35 In the accompanying drawings, illustrating one form of the device of my invention, similar parts are designated by similar numerals.

40 Figure 1 is a top view of one form of the device of my invention.

Figure 2 is a side view of the device of Figure 1.

45 Figure 3 is a top view, partly broken away, of the cosmetic holder of the device of Figure 1.

Figure 4 is a section through the line 4—4 of Figure 1.

Figure 5 is a section through the line 5—5 of Figure 4.

50 The particular form of the device of my

invention shown in the accompanying drawings comprises an annular shell having the inclined side 10 extended outwardly into the peripheral flange 11. The other portion of the shell is inclined downwardly 12 and then inwardly 13, thus forming a cup-shaped member open at both top and bottom.

55 Another annular shell has the inclined side 14 extended outwardly into the peripheral flange 15. The other portion of the shell is inclined upwardly 16 and then inwardly forming the base 17, thus forming a cup-shaped member having a bottom and being open at the top.

60 The two shells are brought into opposed position and fastened together by means of the annular U-shaped member 18.

65 A cover hingedly attached to the one shell at 19, comprises the top 20, the annular flange 21, the bezel 22 and the mirror 23. The flange 21 carries a slight projection 24 capable of fitment within a small depression in the shell side 12. The flange 21 also carries the lift 25.

70 A cover hingedly attached to the other shell at 26 comprises the top flange 27, having a 75 central opening therein, the base 28 and the mirror 29 covering said central opening. The base 28 carries a slight projection 30 capable of fitment within a small depression in the shell side 16. The flange 27 carries the lift 31.

75 A tubular holder 32 is soldered, or otherwise attached to the shell sides 10 and 14, is open at the free end and has an elongated recess 33 therein. In the illustrated device, the side of the holder is inclined downwardly 34, the holder being maintained in position by means of a plurality of tongues 35, 35, formed from cut-outs of the shell sides 12 and 16, the two parts being further attached by means of solder 46.

80 The free end of the holder 32 is open and allows of the introduction of a cosmetic stick 85 holder, 36, closed at one end 37 and open at the other end and having a longitudinal slot 38 therein. Within the stick holder is a cosmetic stick carrier 39 longitudinally movable within the stick holder 36 and having an extended member 40 extending through the slot 38. A cosmetic stick 41 is carried by the carrier 39.

100

Powder compacts 42 and 43, and powder puffs 44 and 45 are positioned within the shell compartments.

My invention is not limited to one exposed 5 mirror and one hidden mirror, as illustrated, as it is evident that both mirrors may be exposed or that both mirrors may be hidden.

It will be noted that my invention presents 10 a container capable of holding, one, or more, powder compacts and one, or more mirrors, and that I overcome the difficulty and awkwardness incident to holding the ordinary container during use of a mirror, by attaching 15 a handle to said container, said handle carrying a cosmetic stick, the usefulness and practicability of my device being evident.

I do not limit myself to the particular size, shape, number or arrangement of parts as 20 shown and described, as these are given simply for the purpose of describing my invention.

What I claim is:—

1. A cup-shaped shell member open at the 25 top and bottom, a second cup-shaped shell member closed at the bottom and open at the top, the two shell members being affixed to each other with their openings outwardly positioned, a cover for each shell opening, a hollow handle open at its outer end carried 30 by said shells and a removable cosmetic stick holder within said handle.

2. In a cosmetic container, in combination, 35 a shell having openings within the opposite faces thereof, a partition extending transversely within said shell, a cover carried by the outer face of each side of said shell, a mirror carried by each cover, a hollow handle open at the outer end carried by said shell and a removable cosmetic stick holder with- 40 in said handle.

3. A cup-shaped shell member open at the 45 top and bottom, a second cup-shaped shell member closed at the bottom and open at the top, the two shell members being affixed in each other with their openings outwardly positioned, a cover for each shell opening, a mirror carried by each cover, a hollow handle open at the outer end carried by said shells and a removable cosmetic stick holder within 50 said handle.

4. A cup-shaped shell member open at the 55 top and bottom, a second cup-shaped shell member closed at the bottom and open at the top, the two shell members being affixed to each other with their openings outwardly positioned, a cover for each shell opening, and a rigid handle projecting radially from said shell members.

60 5. A container comprising two compartment sections each open on one side, independently operable covers mounted on said sections and affording access to the respective compartments, and means permanently se- 65 curing said compartment sections together in

fixed relation with their other sides in abut-
ting face to face contact.

Signed at New York city in the county of
New York and State of New York this 18th
day of July, 1929.

ALEXANDER MOODIE.
